Primary Examiner — Kevin Rudzinski*Assistant Examiner* — Katherine Holbrow(74) Attorney, Agent, or Firm — Robin W. Reasoner; Renee D. Jacowitz(57) CLAIM

The ornamental design for a display screen or portion thereof with icon, as shown and described.

DESCRIPTION

The FIGURE is a front view of a display screen or portion thereof with icon showing my new design.

The broken line showing of a portion of the display screen is for the purpose of illustrating environmental structure and forms no part of the claimed design.

1 Claim, 1 Drawing Sheet(56)
